UNITED STATES PATENT OFFICE.

ARTHUR E. HANDY, OF PROVIDENCE, RHODE ISLAND, ASSIGNOR TO THE RHODE ISLAND ELEVATOR AND MACHINE COMPANY, OF PROVIDENCE, RHODE ISLAND, A CORPORATION OF RHODE ISLAND.

HOISTING-MACHINE.

SPECIFICATION forming part of Letters Patent No. 761,959, dated June 7, 1904.

Application filed August 11, 1903. Serial No. 169,105. (No model.)

To all whom it may concern:

Be it known that I, ARTHUR E. HANDY, a resident of the city of Providence, in the county of Providence and State of Rhode Island, have invented certain new and useful Improvements in Hoisting-Machines; and I do hereby declare that the following is a full, clear, and exact description thereof, reference being had to the accompanying drawings, and to the letters of reference marked thereon, which form a part of this specification.

This invention relates to hoisting-machines, and has for its object the construction of a machine for hoisting which has a drum mounted on eccentrics to be operated by a lever and thrown alternately in and out of frictional contact with driving-rolls and a brake-shoe. This hoisting-drum is locked automatically, making it impossible for said drum to turn back and drop the load while the friction-wheels are being transferred from the friction holding-shoe to the friction driving-rolls.

This hoisting-machine is so constructed that the power-transmitting mechanism is directly connected to and operated by an electric motor, which motor is automatically controlled in its action by the movement of the drum-operating lever and is called into action only when it is desired to turn the drum in the direction necessary to wind up or hoist the load, the motor not being required to run when the load is lowered.

The invention is fully described in this specification and illustrated in the accompanying drawings.

Figure 1 is a plan view of the machine. Fig. 2 is a side elevation showing the locking mechanism and operating-lever partly broken away to show the electrical contact-pieces. Fig. 3 is a detail of the insulated contact-arm thrown down, forming a connection between the contact-pieces, in position to complete the circuit and energize the motor. Fig. 4 is a detail of a portion of the locking-lever, showing the cam attached thereto, which cam controls the movement of the locking-bar. Fig. 5 is a detail side elevation showing as

a modification a depending finger on the locking-lever to engage and operate the locking-bar instead of the cam. Fig. 6 is a detail front elevation showing one frame as partly broken away, the locking-bar projecting through it and engaging the lever on the outside.

Referring to the drawings, A is the base, to which the side frames B B are bolted.

C is the drum-shaft, journaled in eccentrics D D, said eccentrics mounted to turn in bearings in each frame.

F F are two friction-wheels mounted on and fixed to the shaft C on either side of the drum E, which drum is held to move with and on the shaft. Said friction-wheels are held to be thrown alternately into and out of engagement with corresponding friction drive-rolls G G and the brake-shoes H. These brake-shoes are mounted on the rod H' on either side of the machine and in a position to engage each of the friction-wheels, said rod H' being adjustably held at its ends in each frame. The friction-rolls G G are mounted on and fixed to shaft g, which is journaled in each frame. This shaft g is driven by the electric motor I through the pinion J and gear K. The operating-lever R is made in a U shape with its ends extending around on each side of the machine and connected to each eccentric D, which project beyond the frames on either side. The loop of the lever extends out in front of the machine, to which the operating-cord R' is connected.

The lock controlling or lowering lever W is formed into a U shape and extends around the machine similar to that of the starting-lever R. (See Fig. 1.) It is pivoted at both ends at w to the frame B and has cams w' w' fixed at its pivoted ends. This lever W is located below the lever R and is arranged to engage the latter when it is raised for the purpose of unlocking the drum and allowing it to unwind and lower the load.

The arm V is for the purpose of carrying the locking-bar V' and keep it in the proper relation to the friction-wheels F F, with which

it comes in contact. This arm is hung at one end to the drum-shaft C and pivoted to the frame B at its lower end through a slotted hole, which allows said arm an endwise movement to follow the movement of the driven rolls F F when carried by the cams D D. In this arm is a transverse tapering slot V', in which the locking-bar V² works. When the lever W is lowered, the natural tendency of this round 10 bar V² is to roll down the inclined surface of the slot V' by gravity and wedge between the periphery of the driven rolls F and the lower side of the slot, thus effectually preventing the drum, which is connected to the same shaft as the friction-wheels, from turning back in the direction of the arrow and lowering the load.

n is the dog-actuating pin, which projects inward through the lever R to engage and 20 operate the dog M and throw the contact-arm to make and break the connection to the driving-motor, the upper ear m being set off at such an angle to the lower ear m' that it is impossible for the lever R to be raised way 25 up, which is the position required to bring the friction-wheel F in contact with driving-rolls G G, without throwing the dog M and contact-arm L into the contact-fingers N N, as illustrated in Fig. 3 and also in dotted 30 lines in Fig. 2, which position completes the circuit and starts the motor. It is almost impossible to drop the lever from this position without reversing the movement of the dog drawing the arm L from the contact-plates N N and stopping the motor. This contact-arm L and dog M are pivoted to the frame at i, the arm being connected to the dog M through insulating-pieces l. At o is a double-spring finger which receives and retains the 40 lever when drawn out of the contact-fingers N N and thrown up by the movement of the lever R as it is lowered from its raised position.

The operation of the machine is further explained, as follows: The hoisting-drum and 45 the larger friction-wheel connected thereto are eccentrically mounted in the frames to be operated by a lever and thrown into and out of engagement with either the driving-rolls G G to wind up the drum or thrown against 50 the shoe H and held with sufficient pressure to hold the load and prevent the drum from turning back.

In this class of hoisting-machine it has been 55 customary to construct the machine so that during the time the large friction-wheels are being carried by the hoisting-lever from the friction holding-shoe H to small driving-rolls and back again the drum is entirely free to turn back and drop the load which is its purpose to hoist and hold. In using a machine of this character a careless operator or a slight 60 catch in the controlling-rope has often allowed the load to fall, causing serious damage. By the use of my automatic locking device the

danger of dropping the load is entirely obviated, as the hoisting-drum is never released except when the load is desired to be lowered. In using this locking attachment I employ two controlling-ropes, one for hoisting and one for lowering. When it is desired to hoist, 65 lever R is raised and the friction-wheel F is transferred from the holding-shoe H to the driving-rolls G G. By the arrangement of the lock roll or rod V² the drum may turn forward, but is held from turning backward by 70 the wedging of the roll against the periphery of friction-wheel F. When the load has been raised, the lever R is dropped and the friction-wheels return to the friction holding-shoes H. When it is desired to lower the 75 load, the lever W is raised, which draws the locking-roll V² out of contact with the friction-wheel F by the pressure of the cam or finger V' against it. The lever W continues upward until it engages the lever R, which it 80 also draws upward, raising the friction-wheels F F from the holding-shoes H H, and the load is allowed to descend at the will of the operator. The current to the motor comes in on the wire r, and when the contact-arm L is 85 down and the circuit is completed between the fingers N and N the electric switch T is energized, drawing up the bar r² against the points a a, and the circuit is completed, the motor energized, and the friction driving- 90 rolls revolved.

I construct my machine with two large friction-wheels F F and a corresponding number of small friction drive-rolls G G to increase the efficiency of the machine.

It is considered of great practical advantage to have this hoisting mechanism connected to and driven direct by an electric motor and have this motor controlled automatically by the movement of the drum-operating lever R, this motor being called into action only when it is desired to hoist the load, being at all other times entirely disconnected from the drum and also from the electric current.

Having thus described my invention, what 110 I claim as new, and desire to secure by Letters Patent, is—

1. In a hoisting-machine the combination of a hoisting-drum, friction-wheels eccentrically mounted, friction holding-shoes arranged 115 to engage the periphery of said wheels, friction driving-rolls also arranged to engage the periphery of said wheels, means including eccentrics for transferring said friction-wheels alternately from said shoes to said driving-rolls, means for automatically energizing a motor to rotate said driving-wheels and drum to hoist the load when said wheels are brought in contact with said rolls, substantially as described.

2. In a hoisting-machine, the combination of a hoisting-drum, friction-wheels eccentrically mounted, friction holding-shoes arranged 120

to engage the periphery of said wheels, means including eccentrics for transferring said friction-wheels alternately from said shoes to said driving-rolls, means for automatically locking said drum from turning in one direction while being moved between said shoes and said driving-rolls, substantially as described.

3. In a hoisting-machine, the combination of a hoisting-drum, friction-wheels eccentrically mounted, friction holding-shoes arranged to engage the periphery of said wheels, friction driving-rolls also arranged to engage the periphery of said wheels, means including eccentrics for transferring said friction-wheels alternately from said shoes to said driving-rolls, means for automatically locking said drum while being transferred between said shoes to said driving-rolls, means for automatically energizing a motor to rotate said driving-wheels and drum to hoist the load when said wheels are brought in contact with said rolls, substantially as described.

4. In a hoisting-machine, the combination of a hoisting-drum, friction-wheels, friction holding-shoes arranged to engage the periphery of said wheels, friction driving-rolls also arranged to engage the periphery of said wheels, eccentrics in which said wheels are mounted, an operating-lever engaging said eccentrics by which they are turned to move said wheels alternately into and out of engagement with said shoes and said driving-rolls, a contact-arm, contact-finger, means for throwing said arm into and out of engagement with said fingers to make and break the circuit for the purpose of starting and stopping a driving-motor when said lever is raised or lowered respectively.

5. In a hoisting-machine, the combination of a hoisting-drum, friction-wheels, friction holding-shoes arranged to engage the periphery of said wheels, friction driving-rolls also arranged to engage the periphery of said wheels, eccentrics in which said wheels are mounted, an operating-lever engaging said eccentrics by which they are turned to move said wheels alternately into and out of engagement with said shoes and said driving-rolls, a contact-arm, a dog connected to said contact-arm, contact-fingers, a pin in said operating-lever to engage said dog and throw said arm into and out of contact with said fingers by the movement of said lever up and down, thereby making or breaking the electric circuit to stop and start an electric driving-motor, substantially as described.

6. In a hoisting-machine the combination of a hoisting-drum, friction-wheels, friction holding-shoes arranged to engage the periphery of said wheels, friction driving-rolls also arranged to engage the periphery of said wheels, eccentrics in which said wheels are mounted, an operating-lever engaging said

eccentrics by which they are turned to move said wheels alternately into and out of engagement with said shoes and said driving-rolls, a contact-arm, contact-fingers, means for throwing said arm into and out of engagement with said fingers to make and break the circuit for the purpose of starting and stopping a driving-motor when said lever is raised or lowered respectively, means for automatically locking said drum while being moved between said shoes and said driving-rolls, substantially as described.

7. In a hoisting-machine, the combination of a hoisting-drum, friction-wheels eccentrically mounted, friction holding-shoes arranged to engage the periphery of said wheels, friction driving-rolls also arranged to engage the periphery of said wheels, means including eccentrics for transferring said friction-wheels alternately from said shoes to said driving-rolls, a roll lock-bar arranged to engage and be wedged against the periphery of the friction-wheels to hold said wheels from turning in one direction, means for drawing said rolls out of contact with said wheels, substantially as described.

8. In a hoisting-machine, the combination of a hoisting-arm, friction-wheels eccentrically mounted, friction holding-shoes arranged to engage the periphery of said wheels, friction driving-rolls also arranged to engage the periphery of said wheels, means including eccentrics for transferring said friction-wheels alternately from said shoes to said driving-rolls, a gravity-roll lock-bar arranged to engage and be wedged against the periphery of the friction-wheels to hold said wheels from turning in one direction, a controlling-lever, means on the end of said lever by which said bar is drawn out of engagement with said wheel, substantially as described.

9. In a hoisting-machine, the combination of a hoisting-drum, friction-wheels eccentrically mounted, friction holding-shoes arranged to engage the periphery of said wheels, friction driving-rolls also arranged to engage the periphery of said wheels, means including eccentrics for transferring said friction-wheels alternately from said shoes to said driving-rolls, means for automatically locking said drum from turning in one direction while being moved between said shoes and said driving-rolls, a controlling-lever for unlocking said drum, means by which said drum is unlocked and said wheels raised from the friction-shoes by the upward movement of said controlling-lever, substantially as described.

10. In a hoisting-machine, the combination of a hoisting-drum, friction-wheels eccentrically mounted, friction driving-rolls arranged to engage the periphery of said wheels, means including eccentrics for moving said friction-wheels into and out of engagement with said

driving-rolls, means for automatically locking
said drum from turning backward, means for
releasing the lock to lower the load, means for
automatically energizing a motor to rotate
5 said driving-wheels and drum to hoist the load
when said wheels are brought in contact with
said rolls, substantially as described.

In testimony whereof I have hereunto set
my hand this 1st day of August, A. D. 1903.

ARTHUR E. HANDY.

In presence of—

HOWARD E. BARLOW,
E. I. OGDEN.
